UNITED STATES PATENT OFFICE.

JACOB JACOBSEN, OF NEW YORK, N. Y.

SOAP-CUTTING MACHINE.

SPECIFICATION forming part of Letters Patent No. 537,420, dated April 9, 1895.

Application filed June 7, 1894. Serial No. 513,781. (No model.)

To all whom it may concern:

Be it known that I, JACOB JACOBSEN, a subject of the King of Sweden and Norway, residing in the city, county, and State of New York, have invented certain new and useful Improvements in Soap-Cutting Machines, of which the following is a specification.

This invention has reference to an improved machine for cutting a block of soap successively, first into slabs, then into bars, and lastly into cakes of the required size, so that a considerable saving in time and labor is obtained and the cutting up of a block of soap into cakes greatly facilitated and expedited; and the invention consists in its general features of a soap-cutting machine, which comprises an elevator for receiving the block of soap, means for intermittently lifting the elevator, a horizontal reciprocating-frame provided with two pivoted pushers and a horizontal cutting-wire at one end of the frame for cutting off a slab from the block, which slab is then moved by the first pusher with the frame and by the next motion of the frame taken up by the second pusher and pushed through stationary vertical cutting-wires so as to be cut into bars. The bars thus obtained are next placed in front of a laterally-reciprocating pusher, which forces the bars through a second series of vertical cutting-wires arranged in a stationary frame at right-angles to the first set of vertical cutting-wires, so as to cut the bars into cakes, the laterally-reciprocating pusher being hinged to its frame so as to pass over the bars that are fed forward by the next motion of the horizontally-reciprocating frame.

The invention consists further of means for intermittently lifting the elevator so that the block of soap is successively subjected to the action of the cutting-wire for being cut into slabs, said transmitting mechanism being operated when the reciprocating frame has cleared entirely the block of soap.

The invention consists, lastly, of certain mechanisms by which motion is imparted at the proper time to the different operative parts of my improved soap-cutting machine, as will be fully described hereinafter and finally pointed out in the claims.

In the accompanying drawings,—Figure 1

represents a side-elevation of my improved soap-cutting machine. Fig. 2 is a plan-view of the same. Fig. 2^a is a vertical longitudinal section of one form of reversing mechanism employed in my soap-cutting machine. Fig. 3 is a plan-view, drawn on a larger scale and showing the mechanism for transmitting motion from the driving-shaft to the different operative parts of the machine. Fig. 4 is an end-elevation of the left-hand end of the machine. Fig. 5 is a vertical transverse section on line 5—5, Fig. 2. Fig. 5^a is a detail vertical transverse section on line 5^a, 5^a, Fig. 2, seen in the direction of the arrow, Fig. 2; and Figs. 6, 7, and 8 are detail vertical longitudinal sections, drawn on a larger scale, of the longitudinally-reciprocating frame by which the soap-block is cut into slabs and the slabs then moved forward and passed through the first set of vertical cutting-wires.

Similar letters of reference indicate corresponding parts.

Referring to the drawings, A represents the supporting-frame of my improved soap-cutting machine, which is provided at one end with upright and transversely-braced standards A', on which the elevator E, by which the block of soap is intermittently lifted, is placed. At the other end of the frame A is arranged at right-angles thereto an auxiliary frame A², on which are supported the bearings for the driving-shaft S, to which rotary motion is imparted by suitable pulleys, a straight belt and a cross-belt, from a suitable counter-shaft.

On the main-frame A is guided on suitable ways a horizontal, longitudinally-reciprocating frame B, which is provided with longitudinal side-rails b^x and at its extreme right-hand end with a stationary horizontal cutting-wire b, and above the same with a pusher B', pivoted to lugs b' on the side-rails of frame B. Near the middle portion of the frame B is arranged a second pusher B² which is pivoted to lugs b² attached to the top of the side-rails of the frame B, and which is provided with a hinged block B³ having slits b³ in the body of the same. The distance between the pushers B' B² is of such length that a slab which is cut off from the block of soap by the horizontal cutting-wire b of the frame B can

be readily placed in the space between the pushers. The standards A' of the elevator-frame support also rails B⁴ on which the frame B is guided, so that the latter can be moved 5 from one pair of standards to the other pair and entirely over the block of soap supported on the elevator E.

About midway to the length of the main-frame A is arranged a transverse frame C, 10 which is provided with a number of vertical cutting-wires d, said frame being attached to a horizontal platform P, which is supported on the main-frame, directly below the frame B and which extends from a point near the 15 supporting-frame of the elevator to a point near the opposite end of the main-frame B, as shown clearly in Fig. 2. From the transverse frame C extends along one side-rail of the main-frame A, a narrow rail C', which is bevelled at its opposite end, said rail serving as a 20 guide-rail for the slab of soap that is cut off from the block by the horizontal wire b. To the side of the platform P opposite to the rail C', are attached flat springs C² which serve to 25 press the slab toward the stationary guide-rail C' when the same is moved forward by the pusher B' and pressed through the vertical cutting-wires of the transverse frame C.

To the elevator E is imparted an intermittent motion so that the block of soap which 30 is placed on the same, is raised for the required height above the horizontal platform P of the main-frame, and thereby subjected to the action of the horizontal cutting-wires b when the frame B is moved over the block 35 of soap so that a horizontal slab is cut off from the block. The required intermittent motion is imparted to the elevator-platform E by means of rack-bars e that are attached 40 to each corner of the elevator E and guided in ways e^x of the standards A'. With each rack-bar e meshes a pinion e', which are applied in pairs to two transverse shafts e² which turn in bearings of the supporting-frame A', 45 as shown in Figs. 2 and 5, said shafts being turned simultaneously so that all the rack-bars are raised at the same time. To the end of one of the shafts e² is applied a ratchet-wheel e⁸, which is engaged by a spring-pawl 50 e⁴, the teeth of the ratchet-wheel e⁸ being proportioned in such a manner that by the engagement of the pawl with the teeth of the ratchet-wheel the exact height to which the elevator is to be lifted, is controlled, so that 55 slabs of uniform thickness are cut from the block. Rotary motion is intermittently transmitted to the transverse pinion-shafts e² by means of an endless sprocket-chain e⁵, which passes over a sprocket-wheel e⁶ of the same 60 size on each shaft e². One of the shafts e² is further provided with a sprocket-wheel e⁷, to which rotary motion is transmitted by a sprocket-chain e⁸ and several intermediate sprocket-wheels and chains e⁹, e¹⁰, e¹¹, e¹², e¹³ 65 and e¹⁴ from a sprocket-wheel e¹⁵ on the driving-shaft S. The driving-shaft S also transmits motion by a pinion f to a gear-wheel f',

which is applied to an intermediate shaft f² that is supported in suitable bearings below the platform P, said auxiliary shaft f² transmitting motion by means of a pinion f³ to a gear-wheel f⁵ on a second intermediate shaft f⁴ and from said shaft f⁴ by means of a pinion f⁶ and gear-wheel f⁷ on a third intermediate shaft f⁸, which is likewise supported in 70 bearings of the supporting-frame A, to a longitudinal rack-bar f⁹, at the under side of the frame B, as shown in Figs. 3 and 4.

The frame B is provided with a transverse piece B⁵ below the platform P, which piece is 75 attached by bolts to the side-rails of the frame B and to which piece B⁵ is applied a longitudinal piece B⁶, that carries the rack-bar f⁹, as shown in Fig. 3.

When the driving-shaft S is rotated in one 80 direction, motion is imparted by the intermediate transmitting gears to the rack-bar f⁹ and the frame B in one direction, while when the motion of the driving shaft S is reversed, the rack-bar f⁹ and frame B is moved in an 85 opposite direction. The reversing of the driving-shaft S is accomplished at the proper time by any approved reversing device, one form of frictional reversing mechanism being shown in plan in Fig. 2 and in detail vertical 90 section in Fig. 2^a.

To one end of the transverse piece B⁵ of the frame B is attached a block B⁷, which carries a horizontal tongue B⁸, which is tapered off at the ends and provided at its under side with 100 heel-pieces b⁸ and a curved channel b⁷ between the same, as shown in Figs. 1 and 3, said heel-pieces serving to engage an anti-friction-roller b⁹ at the end of a fulcrumed lever B⁹, that engages by its opposite end the 105 movable member of a clutch B¹⁰. The stationary member of the clutch B¹⁰ is attached to the sprocket-wheel e¹⁵, so that the sprocket-wheel is at rest when the movable member is 110 out of gear with the stationary member of the clutch, but is turned by the driving-shaft as soon as the movable member is thrown into gear with the stationary member of the clutch. This is accomplished by the heel-pieces b⁸ of 115 the tongue B⁸ when the frame B is moved forward over the platform, as the roller b⁹ of the lever B⁹, passes first along the inner edge of the first heel-piece, then outwardly on the channel b⁷ and then along the outer edge of the second or longer heel-piece b⁸. When the tongue B⁸ 120 is not in engagement with the lever B⁹, the latter is pressed inwardly by the action of a helical spring b¹¹, which is interposed between the outer end of the lever B⁹ and the upper end of a spring-arm B¹¹ that is pivoted to one 125 of the horizontal side-pieces of the frame A², as shown in Figs. 1, 2 and 4. By the pressure of the spring b¹¹, the opposite end of the lever B⁹ holds the movable member of the clutch B¹⁰ out of gear with the stationary 130 member on the sprocket-wheel e¹⁵, so that the latter is not turned by the driving-shaft. When the tapering longer heel-piece b⁸ of the tongue B arrives at the end of the lever B⁹ it

engages the roller b^9 and turns the lever on its fulcrum against the tension of the spring b^{11} so that its opposite end moves the movable member of the clutch into gear with the stationary member, whereby the sprocket-wheel e^{15} is turned and the elevator raised by the action of the intermediate sprocket-chains and sprocket-wheels on the pinion-shafts and rack-bars of the elevator, so that the block 10 of soap is lifted for the required thickness of the slab to be cut off. The movable member of clutch B^{10} remains in gear as long as the roller b^9 is held in engagement with the edge of the longitudinal piece b^8 of the tongue 15 B^8 . When the roller b^9 arrives at the opposite end of the heel-piece b^8 , the lever B^9 is shifted again by the action of the spring b^{11} , the clutch-members are thrown out of gear, the motion of the transmitting mechanism 20 and elevator is interrupted and the block of soap prevented from being raised farther, so as to be ready for the action of the horizontal cutting wire b . This takes place when the frame B has moved the slab of soap, cut during the outward motion of the frame, over the platform P and through the series of vertical cutting-wires d . During the outward motion of the frame B, the cutting-wire b passes again through the raised block of soap and 25 cuts off another slab, which is engaged by the first pusher B' , that drops into vertical position when it arrives at the end of the slab, so as to take the slab along. The block B^3 of the second pusher B^2 drops at the same time 30 into vertical position back of the slab before cut off, so that on the reversal of the motion of the driving-shaft by the reversing mechanism the reciprocating-frame B is moved in forward direction, and its pushers B^2 and B' carry 35 both slabs of soap forward, the foremost slab being pressed by the block B^3 through the vertical cutting-wires, while the rear slab is moved over the block of soap onto the right-hand end of the platform P, as shown in Fig. 8. The edge 40 of the platform P is beveled as shown in Figs. 6, 7 and 8, so that the slab is readily transferred to the same from the block of soap. While the foremost slab is forced by the pusher-block B^3 through the cutting-wires d , it is 45 steadily and guided by the side-rail C' and flat springs C^2 . The pusher-block B^3 moves the slab entirely beyond the cutting-wires d , which is accomplished by the slits b^3 in the same, into which the cutting-wires enter, so 50 that the slab is cut for its entire length into bars of soap. The tongue B^8 throws the clutch B^{10} into gear, so that the block of soap on the elevator is again raised, while simultaneously the motion of the driving-shaft and frame B 55 is reversed, and thereby the cutting-wire b moved again through the block so as to cut off another slab, while the pushers B^3 and B' pass over the slab on the platform and over the slab just being cut off from the block, as 60 shown in Fig. 6. When the frame B arrives at its outermost position, the pushers B^3 and B' drop respectively into vertical position, as

shown in Fig. 7. The motion of the frame B being now reversed, the slab on the platform and the slab just cut off are moved forward 70 by the pushers B^3 and B' so that one is forced through the vertical cutting-wires d and the other moved on to the platform P, as shown in Fig. 8.

During the forward motion of the pushers 75 B^3 and B' , they abut against stop-pins b^x b^x which are attached to the side-rails of frame B immediately back of the pushers B^3 and B' , as shown in Figs. 6, 7 and 8.

At the end of the platform and located opposite to the transverse frame A^2 , and beyond the transverse cutting-frame C, is arranged a transversely-reciprocating pusher-bar D, which is hinged to a frame D' , that is guided on ways D^2 of the auxiliary frame A^2 , said 80 frame D' being provided with a transverse piece D^3 having a stationary screw-nut S' , which is engaged by a screw-threaded portion of the driving-shaft S, as shown in Fig. 2. When the bars of soap are pushed on to the 85 end of the platform P, so as to be in front of the pusher-bar D, the latter is moved across the platform by the action of the threaded portion of the driving-shaft S on the screw-nut S' . The bars are thereby moved through 90 a second series of vertical cutting-wires g which are supported in a longitudinal frame G that is arranged parallel with the pusher-bar D at the opposite side of the platform P, so that the bars are cut up into a number of 95 cakes, which are moved on to a slightly-inclined platform P' and then to a suitable conveyor, or on to drying racks, on which the cakes are separated, and then conducted to the drying-room.

As soon as the bars are cut up into cakes 100 by the cutting wires g , the motion of the driving-shaft S is reversed by the action of the transverse piece D^3 of the frame D' on one of two pins D^5 arranged on a shifting-rod D^4 , so 105 that the latter is shifted in the direction of the motion of the frame D' , whereby a forked lever D^6 which is fulcrumed to the rod D^4 , is also shifted in the same direction. Lever D^6 moves a sliding sleeve D^7 which is placed loosely on 110 the shaft S and produces thereby by the connecting parts the tightening of one of the driving-pulleys D^8 on the shaft S and the loosening of the other, so that the belt on the former pulley transmits motion to the driving shaft 115 and reverses the motion of the same, while simultaneously the transmitting action of the cross belt and loose pulley on the driving shaft is discontinued, in the same manner as in other well-known constructions of reversing 120 mechanisms.

During the return-motion of the reciprocating-frame D' , which is produced by the reversal of the motion of the driving-shaft, the hinged pusher-bar D passes over the rounded-off end of a spring-piece G' , that is attached at its opposite end to a block G^2 that extends transversely across the platform P at the end 130 of the same. During the forward motion of

the pusher-bar D, the latter lifts by its projecting end g^2 the curved outer end of the spring piece G, as shown in Fig. 5^a and sufficiently to clear the same. During the return-
5 motion of the pusher-bar D over the spring-rail G', the pusher-bar is lifted so as to pass above the bars that are moved onto the end of the platform P by the next forward motion of the reciprocating-frame B. When the
10 frame D' arrives at the end of its return-motion, the pusher-bar D clears the recessed end g^3 of the transverse block G², and drops again into vertical position, so as to be in a position to push the next set of bars transversely across
15 the platform and through the vertical cutting-wires g, by the next forward motion of the pusher-bar D, which is accomplished by the action of the transverse piece D³ on the second pin D⁵ on the shifting rod D⁴, whereby the re-
20 versing mechanism is again actuated and the motion of the driving shaft reversed.
A stop b¹² is attached to the side-rail of the frame D' and adapted to pass along an inclined portion b¹³ of the spring-arm B¹¹, which
25 is pivoted to the frame A², said stop raising the spring-arm until it has passed the inclined portion and arrives at the straight end b¹⁴ of the arm B¹¹. The raising of the spring-arm B¹¹ exerts a tension on the spring b¹¹, so that
30 the anti-friction roller b⁹ of the fulcrumed, clutch operating lever B¹⁹ is moved along the channel b⁷ between the check-pieces b⁸ of the tongue B⁸ on the frame B, so as to secure the reliable engagement of the roller by the rear
35 heel-piece and consequently the reliable working of the clutch at the proper time so as to produce the raising of the elevator. When the motion of the driving-shaft is reversed, the stop b¹² liberates during the forward motion
40 of the slide frame D' the arm B¹¹, so that the spring b¹¹ is pressed on the end of the fulcrumed lever and holds the movable clutch-member in ungeared position, whereby during the return-motion of the frame B, the tongue
45 B⁸ and its heel-pieces b⁸ can clear the roller b⁹.

The operation of the different parts of my improved soap-cutting machine was described in connection with the description of the same, so that only a brief additional description is required.

Before starting the machine, the elevator-platform E is returned to its lowermost position by raising the pawls of the pinion-shafts of the elevator and permitting the downward motion of the platform by gravity. When the platform has arrived at its lowermost point, the block of soap is transferred on to the same from the truck by which it is moved to the cutting-machine. When the block is placed in position on the elevator E, the driving-shaft is started and the block raised to a sufficient height above the platform P, so that by the outward motion of the reciprocating-frame B, the horizontal cutting-wire b passes through the block, while the pusher B' passes over the slab cut off by the wire b. When the end of the reciprocating-frame B arrives

at the opposite side of the block the pivoted pusher B' drops into vertical position, as shown in dotted lines in Fig. 6, and in full 70 lines in Fig. 7. The slab is then in a position so as to be moved by the forward motion of the reciprocating-frame B on to the platform P, as shown in Fig. 8. During the next outward motion of the frame B, the pusher B², 75 with its hinged pusher-block B³, passes over the slab thus cut off, while simultaneously the horizontal cutting-wire passes through the block, which has been raised in the meantime, for the thickness of a slab and cuts off 80 the next slab, the pusher B' passing again over the slab until it arrives at the end of the same and dropping into vertical position back of the same. Simultaneously the pusher B² with its pusher-block B³, drops likewise to 85 the rear of the first slab, so that by the forward motion of the reciprocating-frame B, both slabs are moved forward one toward the end of the platform P and the other from 90 the block on to the platform P, as shown in Figs. 7 and 8. The first slab is pressed by the forward motion of the frame B through the vertical cutting-wires d, so as to be cut into bars, which are moved over the platform P into the path of the pusher-bar D, which 95 moves the bars transversely over the platform and forces them through the cutting-wires g, which are arranged longitudinally alongside of the platform P, so as to be cut into cakes, which are moved onto the platform P', and then conducted from the same on to a suitable conveyer and by the same to the drying chamber. The clutch-mechanism by which the elevator is intermittently raised, as well as the mechanism for changing the 10 motion of the driving-shaft, is operated at the proper time so as to produce the lifting of the block of soap before the forward motion of the reciprocating-frame B commences.

The motion of the reciprocating pusher-bar D and its frame D' is so timed that it moves across the platform P when the bars are in front of the pusher-bar, and back again over the spring-rail G', of the side-block G² so as to pass over the next set of bars, when the 11 direction of motion of the driving-shaft is changed by the reversing mechanism. When the elevator is raised sufficiently so that the block is cut up entirely into slabs, the elevator is returned into its lowermost position, 12 so as to receive the next block of soap, upon which the machine is again operated in the same manner as before described, so that the block is cut up into horizontal slabs, the slabs into longitudinal bars, and the bars into cakes. 13

Having thus described my invention, I claim as new and desire to secure by Letters Patent—

1. The combination, with an intermittently-lifted block-carrying elevator, of a longitudinally-reciprocating frame provided with a horizontal cutting-wire at the outer end of the same and two pivoted pushers supported at different points of the same, a horizontal

platform for receiving the slabs cut off from the block, and a stationary frame provided with vertical cutting-wires arranged transversely to the platform, substantially as set forth.

2. The combination, with an intermittently-operated block-carrying elevator, of a longitudinally-reciprocating frame, having a horizontal cutting-wire at one end, a pivoted pusher above said wire, and a second pusher near the middle portion of the frame, a series of vertical cutting-wires arranged transversely across the platform, a transversely-reciprocating pusher-bar arranged at one side of the end of the platform, and a second series of vertical cutting-wires arranged parallel with the pusher-bar at the opposite end of the platform, substantially as set forth.

3. The combination, of a block-carrying elevator, vertically-guided rack-bars attached to the same, pinions engaging said rack-bars, a series of sprocket-wheels and chains for transmitting rotary motion to the pinion-shafts, a horizontal reciprocating-frame provided with a horizontal cutting-wire at its outer end and with pivoted pushers, a driving-shaft, a clutch on the driving-shaft, and means applied to the reciprocating-frame and adapted to throw the clutch in or out of gear so as to transmit motion to the elevator and stop the motion of the same, substantially as set forth.

4. The combination of a horizontal platform, having longitudinal guide-rails, a reciprocating-frame guided on the same, means for imparting reciprocating motion to said frame, a transverse frame extending across the platform and provided with vertical cutting-wires, two pushers pivoted at different points of the reciprocating-frame, and a pusher-block hinged to the pusher nearest to the transverse cutting-frame, said pusher-block being provided with slits so as to pass over the vertical cutting-wires and permit the slab to be moved entirely beyond the same, substantially as set forth.

5. The combination of a horizontal platform, guide-rails at both sides of same, a reciprocating-frame provided with a horizontal cutting-wire and pushers for moving the slabs over the platform, a transverse frame extending across the platform and provided with vertical cutting-wires, a stationary guide-rail extending from said transverse frame along one of the side guide-rails of the reciprocating-frame and flat springs attached to the opposite side of the platform and adapted to press the slab against the stationary rail while the same is forced through the vertical cutting-wires, substantially as set forth.

6. The combination, of a horizontal platform, a transversely-guided frame, means for moving the frame transversely over said platform, a pusher-bar hinged to the end of the transverse reciprocating-frame, a stationary frame arranged at the opposite side of the platform and provided with a series of vertical cutting-wires, a grooved transverse block-rail arranged at the end of the platform, and a spring-rail attached to the top of the block and having a rounded off outer end adapted to engage the pusher-bar and lift the same during its return-motion, so as to pass over the bars of soap on the platform, substantially as set forth.

7. The combination of a horizontal supporting platform, having longitudinal guide-rails, a reciprocating frame guided on the same and provided with a horizontal cutting-wire at the end and pivoted pushers, a rack-bar attached to the reciprocating-frame below the platform, a driving-shaft, a reversing mechanism for said shaft, and intermediate gearing between the driving-shaft and the rack-bar for imparting reciprocating motion to the same, substantially as set forth.

8. The combination, of a block-carrying elevator vertical rack-bars attached to said elevator, pinions engaging said rack-bars, a pawl and ratchet-wheel mechanism applied to one of the pinion-shafts so as to control accurately the lifting motion of the elevator, a driving-shaft, a clutch on said shaft and intermediate transmitting mechanism between the clutch and the pinion-shaft for imparting an intermittent lifting motion to the elevator, substantially as set forth.

9. The combination, of a block-carrying elevator, a horizontal platform, a reciprocating-frame, having a horizontal cutting-wire and pushers for moving the cut-off slabs over the platform, a driving-shaft, a clutch on said driving-shaft, a tongue attached to the reciprocating-frame, below the platform, a fulcrumed and spring-pressed lever engaging the movable member of the clutch, and transmitting mechanism between the clutch and the elevator for intermittently raising the same, said clutch being thrown in or out of gear by said tongue so as to start or stop the raising mechanism of the elevator, substantially as set forth.

In testimony that I claim the foregoing as my invention I have signed my name in presence of two subscribing witnesses.

JACOB JACOBSEN.
